Primary Examiner — Michelle E. Wilson*Assistant Examiner* — Clese Moore, Jr.(74) *Attorney, Agent, or Firm* — Daryl R. Wright; Greg Carr(57) **CLAIM**

The ornamental design for a model vehicle center skid plate as shown and described.

DESCRIPTION

FIG. 1 is an upper, left, front perspective view of a model vehicle center skid plate showing our new design;

FIG. 2 is a front elevation view thereof;

FIG. 3 is a rear elevation view thereof;

FIG. 4 is an upper plan view thereof;

FIG. 5 is a lower plan view thereof;

FIG. 6 is a right side elevation view thereof;

FIG. 7 is a left side elevation view thereof;

FIG. 8 is an upper, right, rear perspective view thereof; and, FIG. 9 is a lower, right, rear perspective view of the model vehicle center skid plate.

In the drawings, the broken lines illustrate portions of the model vehicle center skid plate that form no part of the claimed design.
